UNITED STATES PATENT OFFICE.

HENRY T. BAYNES, OF BUFFALO, NEW YORK.

DESIGN FOR A PIPE.

SPECIFICATION forming part of Design No. 34,778, dated July 16, 1901.

Application filed March 20, 1901. Serial No. 52,104. Term of patent 3½ years.

To all whom it may concern:

Be it known that I, HENRY T. BAYNES, a citizen of the United States, residing at Buffalo, in the county of Erie and State of New York, 5 have invented a new and original Design for Pipes, of which the following is a specification, such as will enable others skilled in the art to which it appertains to make and use the same, reference being had to the accompanying drawing, forming part thereof.

In the drawing the figure is a side elevation of a pipe arranged according to my invention.

As shown in the drawings, the bowl of the 5 pipe is made to conform with the head of a buffalo or bison 1, from the rear of which a stem-securing sleeve 2 projects to receive the stem 3.

The leading feature of the design consists in so forming the bowl of the pipe as to produce a representation of a buffalo or bison head having a rearwardly-projecting sleeve near its lower end, as shown in the drawing.

Having thus described my invention, what I claim, and desire to secure by Letters Patent, is—

The design for a pipe, substantially as herein shown and described.

In testimony whereof I have signed my name to this specification in the presence of two subscribing witnesses.

HENRY T. BAYNES.

Witnesses:

DANIEL MCINTOSH,
O. E. HODDICK.
